ADJUSTABLE SCREEN AND WINDOW FOR
AUTOMOBILES

Max Grishkevich, Gary, Ind.

Application May 28, 1938, Serial No. 210,773

2 Claims. (Cl. 268—133)

This invention relates to automobile windows and the general object of the invention is to provide means whereby a window may be raised or lowered or a screen raised or lowered or both raised or lowered at the will of the occupant.

Another object is to provide means for positively shifting the screen and window and holding them in adjusted position.

The invention is illustrated in the accompanying drawings wherein:

Fig. 1 is an inside elevation of a window casing such as used for automobiles, showing the screen closed.

Fig. 2 is an elevation of the window casing 15 with the inside plate removed, showing the screen raised and the glass pane lowered.

Fig. 3 is a section on the line 3—3 of Fig. 2.

Fig. 4 is a vertical section on the line 4—4 of Fig. 3.

Fig. 5 is a section on the line 5—5 of Fig. 2.

Fig. 6 is a section on the line 6—6 of Fig. 2.

In these drawings I have illustrated my invention applied to the door of an automobile, and the metallic casing of this door is designated generally 10. The window opening is designated 11, the lower edge of this window opening being defined by an inwardly and upwardly extending flange 12, the ends of the window opening having inwardly extending flanges 13. Disposed within the metallic casing of the window is a supporting frame for the window which may be made of wood or other suitable material. This supporting frame has side members 14 which are grooved at 15 for engagement with the margins of the glass pane 16. Inward of this groove 15, the members 14 are formed with the groove 17 for engagement with the screen designated generally 18. The curved upper element 19 of the wooden frame 40 is correspondingly grooved for the reception of the upper edge of the glass pane and the upper edge of the screen. The base of this frame is designated 20.

For the purpose of operating the glass pane 16, 45 I provide a vertically disposed screw 21, whose lower end is supported in a pair of spaced plates 22 and 23. Between these plates and carried by the lower end of the screw 21 is a gear wheel 24. This meshes with a gear wheel 25 and the gear wheel 25 in turn meshes with a gear wheel 26 having the upper ends of the teeth beveled to constitute a beveled gear wheel.

Mounted between plates 27 and 28 is a gear wheel 29 having beveled gear teeth which mesh 50 with the gear wheel 26 and this gear wheel 29

in turn meshes with a gear wheel 30 of much larger diameter mounted between the plates 27 and 28. The shaft 31 of the gear wheel 30 extends through the inside plate 32 of the door casing and is provided with a crank handle 33, thus the train of gears 30, 29, 26, 25 and 24 may be rotated in either direction by rotating the handle 33 in either direction. Clamped upon the lower edge of the glass pane 16 is a traveling nut 34 having threads engaging the threads of the screw 21. 10 It will be obvious now that by rotating the screw 21 in one direction or the other, that the glass pane may be slid up or down to a closed or an opened position, as desired.

The screen 18 is embraced at its margin by 15 a metallic frame 35 and mounted upon the lower edge of this frame is a traveling nut 36 of the same character as the nut 34. This is engaged by the vertical screw 37 in turn driven through the train of gears 38, 39, 40 and 41, the gear 20 wheel 41 being relatively large and having its shaft 42 extending through the rear plate of the window casing and provided with the crank handle 43. The gear wheels 38, 39, 40 and 41 are of precisely the same character as the gear wheels 24, 25 26, 27 and 30, but inasmuch as the screen frame operates inward of the glass pane and inasmuch as the screw 37 must be set inward of the screen frame, there is no necessity for an intermediate gear wheel such as the gear wheel 25. It will be 30 seen that the inwardly extending flange 12 of the outer casing plate will extend inward over the upper end of the mechanism for lifting the glass pane and to a point nearly touching the glass pane, and that the flanges 13 will also extend inward nearly to the groove 15. 35

The operation of the mechanism is obvious from what has gone before. By rotating the handle 33, the glass pane may be raised or lowered and by rotating the handle 43, the screen 40 may be raised or lowered. By this means, both the screen and the window pane may be raised or both lowered, or one raised or the other lowered. It will be likewise noted that this mechanism is not liable to jam, that it is very powerful 45 because of the screw action, and that the window or screen will be held in any adjusted position against movement either up or down.

It will likewise be noted that in case of breakage, the window pane or the screen frame may be 50 readily removed and replaced.

What is claimed is:

1. In a structure of the character described, a body formed to provide a window opening and a chamber lying beneath said opening, the lower 55

- part of the window opening forming a sill separating it from said chamber, said sill having a slot formed therethrough and extending the width of the opening, a closure member for the window opening, comprising a flat body of the same edge contour as the opening and adapted to be moved vertically through said sill slot into the window opening, a screw disposed vertically within the chamber at one side of said slot, a nut 5 carried by said closure body and threaded upon said screw, said screw being supported for rotation, a spur gear carried upon the lower end of said screw, a beveled gear mounted adjacent the spur gear for rotation on an axis parallel with the screw, said beveled gear having radial teeth meshing with the spur gear, a second beveled gear in mesh with said first beveled gear and supported at one side of the screw for rotation upon an axis perpendicular to the screw, said 10 second beveled gear having radial peripheral teeth forming a spur gear, a spur gear rotatably supported above and in mesh with the spur gear teeth of the second beveled gear, and crank means for rotating said second spur gear whereby rotary motion may be imparted to said screw to effect movement of the nut and closure body connected therewith.

2. In a structure of the character described, a body formed to provide a window opening and a chamber disposed below the window opening, the top wall of the chamber forming the sill of the window opening and the chamber having a bottom wall and vertical side walls, said top wall having a slot therethrough extending the full width of the window opening, a flat closure mem-

ber having a peripheral contour corresponding to the outline of the window opening and movable vertically through said slot from within the chamber to closing position with respect to the opening and vice versa, a plate member disposed in the lower part of said chamber in spaced parallel relation with the bottom wall thereof, said plate member including a vertical side portion disposed in spaced parallel relation with a side wall of the chamber, a screw disposed vertically within the chamber and having a lower end portion extending through said plate, a spur gear upon the lower end portion of the screw between the plate and the bottom wall of the chamber, a combined spur and beveled gear mounted for 15 rotation between the plate and bottom wall and having the spur portion engaging said spur gear, the beveled portion of the combined gear extending into the area between the side portion of the plate and the adjacent wall, a combined spur and 20 beveled gear mounted between said side portion of the plate and the adjacent wall for rotation on an axis perpendicular to the screw and having the beveled portion thereof meshing with the beveled portion of the first combined gear, a spur 25 gear rotatably mounted between the side portion of the plate and the adjacent wall and meshing with the spur gear portion of the second combined gear, crank means connected with said last gear for effecting rotation of the same, and a 30 nut secured to the lower part of said closure member and threaded upon said screw.

MAX GRISHKEVICH.
